UNITED STATES PATENT OFFICE.

WALTER R. JENNEY, OF WESTFIELD, MASSACHUSETTS, ASSIGNOR OF ONE-HALF TO CHARLES H. BEALS, OF WESTFIELD, MASSACHUSETTS.

AUTOMATIC SWITCH.

No. 853,882.

Specification of Letters Patent.

Patented May 14, 1907.

Application filed February 14, 1907. Serial No. 357,239.

To all whom it may concern:

Be it known that I, WALTER R. JENNEY, a citizen of the United States, residing at Westfield, county of Hampden, and State of Massachusetts, have invented an Improvement in Automatic Switches, of which the following description, in connection with the accompanying drawing, is a specification, like letters on the drawing representing like parts.

This invention relates to automatic switches, and has for its object to provide a novel switch of this character adapted for either steam or electric roads which may be automatically set for the main line from the movement of the car toward the switch.

I employ in connection with my switch suitable means for locking it, and the automatic means for operating the switch is so constructed that the movement of the car will first unlock the switch and then shift it.

I will first describe one embodiment of the invention and then point out the novel features thereof in the appended claims.

In the drawings, Figure 1 illustrates a portion of a track showing my improved switch; Fig. 2 is a detail hereinafter described; Fig. 3 is a section on the line *x*—*x*, Fig. 2; Fig. 4 is another detail of the connections for unlocking the switch; Fig. 5 is a section on the line *y*—*y*, Fig. 4; Fig. 6 is a section on the line *a*—*a*, Fig. 5; Fig. 7 is a detail of the connections with the switch stand; Fig. 8 is a side view of a portion of Fig. 7; Fig. 9 is a section on substantially the line *b*—*b*, Fig. 10; Fig. 10 is a front elevation and Fig. 11 a side view of a switch-stand of an ordinary form adapted for use in connection with my invention.

Referring to Fig. 1 of the drawings, 3 and 4 designate the main rails of a railroad track, 40 and 5 and 6 the pivoted switch rails which are shown as connected together by a bar 7 as usual. This bar is connected by a link 8 with the crank 9 of a switch-stand of the ordinary type known to the art as the Ramapo switch-stand. This type of switch-stand is well known to those skilled in the art and a detailed description thereof is not necessary, it being sufficient merely to state that the stand contains the vertical shaft 10 to the 45 lower end of which the crank-arm 9 is secured, and on the upper end of which is slidably carried the head 11 having the non-circular locking part 12 that is adapted to engage in a non-circular socket 13 formed in the

member 14. The head 11 is arranged to 55 have sliding motion only on the shaft 10 and is held from rotation thereon. In the operation of these switch-stands when it is desired to throw the switch, the head 11 is lifted by a suitable lever or other means to carry the 60 non-circular portion 12 out of the socket 13, as shown in Fig. 10, when the shaft and head can be turned through a quarter revolution thereby through the crank 9 moving the switch rails, and after the switch rails have 65 been set, they are locked by allowing the head 11 to descend to permit the portion 12 to again enter the socket 13.

In accordance with my invention I have provided an actuator adapted to be actuated 70 by the train for first unlocking the switch and then shifting it. Situated along side of the main rail 4 is a bar or actuator 14 which is shown as carried by pivoted arms 15. This actuator 14 normally stands quite closely adjacent the rail 4, as shown in Fig. 3, and its ends are bent away from the rail slightly so as to permit the flange of a car wheel to enter therebetween. When a train or car passes over the track and the flanges of the 80 wheels do thus enter between the rail and member 14, the latter is swung into dotted line position Fig. 1, and this movement first operates to unlock the switch and then to cause the switch rails to be moved. The 85 arms 15 may be mounted in any suitable way and I have herein shown each of them as having at one end a pivotal-pin 16 which is journaled at both ends in a spider or frame 17 secured to the ties of the track or any other 90 solid base, the other end of each arm 15 having pivotal connection with the member 14. Secured to the member 14 near one end is one arm of a centrally-pivoted lever 18, the other arm of which is connected to a tubular 95 member 20 by means of a suitable swivel connection. The lever 18 is shown as bifurcated at one end and has swiveled thereto the block 21 which is secured to the tube 20, said block being held on the tube 20 between two 100 collars 39 and 40. The other end of the lever 18 is shown as carried under the stock rail 4 and as pivoted to the actuator 14 by means of a pivotal connection 49, said pivotal connection being strengthened by means of a 105 strengthening bridge 50. Said lever 18 is shown as pivoted to a spider or frame 51 which is secured to any suitable support.

The tubular member 20 connects to one arm of a bell-crank 22, the other arm of which is connected to a link 23 that extends to the switch-stand, and has pivoted thereto two 5 crank-arms 24 connected to two vertical shafts 25, one situated on each side of the switch-stand. Each shaft 25 has at its upper end a cam member 26 that is for the purpose of elevating the head 11 thereby to unlock 10 the switch. Each cam member has the low portion 27 and the high portion 28 and is adapted to act on a projection 29 carried by the head 11, each projection 29 preferably having an anti-friction roller 30 thereon to 15 reduce friction. When the parts are in normal position the low portions 27 of the cams 26 are underneath the rolls 30, but when the shaft 25 is turned through a quarter revolution, the high portions of the cams come under these projections, thereby elevating the head 11, as will be obvious.

Situated within the tube 20 is a rod 33 which projects beyond said tube 20 and has at one end a head 34. Situated between the 25 head and the end of the tube 20 is a switch-throwing member in the form of a spring 35 which surrounds the projecting end of the rod 33. The other end of the rod 33 is connected to one arm of a bell-crank 36, the 30 other arm of which is either connected to the rod 8 or the bar 7.

The operation of the switch is as follows: Assuming that the switch is open, that is, the switch rails 5, 6 are set for the siding, the 35 parts will be in the position shown in Fig. 1. As a car comes toward the switch from the right the flanges of the wheels enter between the actuator 14 and the rail 4 and throw said actuator into the dotted line position, the 40 latter swinging about the arms 15 during this movement. This movement of the actuator is a combined movement longitudinally of the track and away from the rails. The longitudinal component of the motion swings the lever 18 about its fulcrum 37, thereby 45 moving the tube 20 to the right Fig. 1 and turning the bell-crank 22 in a direction to shift the link 23 in the direction of the arrow *a*. When the parts are in the position shown 50 in Fig. 1, the low portion 27 of the cams 26 stands under the rolls 30, but when the bell-crank 22 is shifted into the dotted line position Fig. 1, the shafts 25 are turned sufficiently to bring the cams into the position 55 shown in Fig. 10, and in turning into this position they operate to elevate the head 11 and thus unlock the switch. The movement of the actuator 14 into the dotted line position will obviously compress the spring 35 because 60 the switch rails are locked, and no movement of the rod 33 can take place until the switch is unlocked. As soon, however, as the switch is unlocked, the resiliency of the spring 35 operates to throw the rod 33 to the 65 right, thereby shifting the switch rails and

setting them to close the switch. This action of the spring 35 may be augmented, if desired, by a supplemental spring 39 which acts directly on one of the switch rails. If the switch rails 5, 6 are already set for the main line when the car comes along, then the rod 33 will be projected sufficiently to the right Fig. 1 so that the movement of the actuator 14 into the dotted line position will not compress the spring 35. It will thus be seen that 70 with my apparatus a car moving toward the switch will first unlock the latter and then throw it, so that if the switch is open or set for the siding, the train may automatically close the switch or set it for the main line and 75 thus prevent an accident. My improvement further does not interfere in any way with the operation of the switch by hand. Moreover my improvement may be used in connection with various switch-stands, and 80 although I have shown it as used in connection with the ordinary Ramapo switch-stand, I do not wish to be limited thereto. It will be obvious, therefore, that various changes 85 may be made in the construction of the device without departing from the invention.

Having fully described my invention, what I claim as new and desire to secure by Letters Patent is:—

1. In a switch, the combination with a 95 main track and a switch, of means for temporarily locking the switch open for the purpose of directing a train on to the siding, means to unlock said switch by the movement of a train over the main track in the direction of the switch, a switch-throwing member, and means to store up energy therein while the switch is being unlocked whereby when said switch is unlocked the switch-throwing member comes into play to throw 100 the switch.

2. In a switch, the combination with a main track and a movable switch rail, of an actuator extending longitudinally of the main track and adapted to be moved by the movement of a car over the track, a lock for the switch rail, means to release the lock by movement of the actuator, a switch-throwing member, and means to store up energy therein by the movement of the actuator in 110 unlocking the switch whereby when said switch is unlocked the switch-throwing member operates to throw the switch.

3. In a switch, the combination with movable switch rails of an actuator extending 115 longitudinally of the track and adapted to be operated by the movement of the car thereover, a lock for the switch, connections between said actuator and both the switch rails and lock, the connections between the actuator and switch rails being a yieldable one, whereby the movement of the actuator first 120 unlocks the switch rails and then shifts the latter.

4. In a switch, the combination with a 125

- main track and movable switch rails of a switch-stand having a shaft connected to the switch rails and provided with a locking head slidably mounted thereon, and means operated by the movement of the car on the main track in the direction of the switch first to raise the head, thereby to unlock the switch, and then to turn the shaft and throw the switch.
- 5 5. In a switch, the combination with a movable switch rail of a switch-stand having a shaft connected to said switch rail and provided with a locking head slidably mounted thereon, unlocking cams for raising said head thereby to unlock the switch, and means operated by the movement of a car on the main track in the direction of the switch for first operating the cams thereby to unlock the switch, and then to turn the shaft to throw the switch.
- 10 6. In a switch, the combination with movable switch rails of a lock therefor, an actuator extending longitudinally of the track and adapted to be moved longitudinally by the movement of a car over the track, a lever connected to the actuator, connections between said lever and lock, and separate yieldable connections between said lever and switch rails.
- 15 7. In a switch, the combination with movable switch rails of an actuator extending longitudinally of the track and adapted to be operated by the movement of a car thereon, a lock for the switch, non-yieldable connections between said actuator and the lock, and yieldable connections between said actuator and the switch rails whereby the movement of the actuator first unlocks the switch rails and then shifts the latter.
- 20 8. In a switch, the combination with movable switch rails of a switch stand connected thereto and including a lock therefor, an actuator extending longitudinally of the track and adapted to be operated by the movement of a car thereover, connections between said

actuator and the lock portion of the switch stand, and other connections between said actuator and switch stand for throwing the latter after it has been unlocked.

9. In a switch, the combination with movable switch rails of a switch stand connected thereto, a lock for the switch stand, an actuator extending longitudinally of the track and adapted to be operated by the movement of a car thereover, and unyielding connections between said actuator and the lock for the switch stand, and yielding connections between said actuator and the switch stand whereby the switch stand is first unlocked and then operated to throw the switch rails.

50 10. In a switch, the combination with a movable switch rail of a switch stand having a shaft connected to said switch rail and provided with a locking head slidably mounted thereon, a cam for raising said head thereby to unlock the switch, an actuator adapted to be operated by the movement of a car on the track, connections between said actuator and said cam, and yielding connections between said actuator and the shaft of said switch stand whereby the movement of the actuator operates first to unlock the switch stand and subsequently to throw the switch rail.

55 11. In a switch, the combination with a movable switch rail of an actuator adapted to be operated by the movement of a car traveling on the track, a spring for throwing the switch, and means operated by the actuator both to unlock the switch rail and to store up energy in the spring whereby the latter may operate to throw the switch rail after they are unlocked.

In testimony whereof, I have signed my name to this specification, in the presence of two subscribing witnesses.

WALTER R. JENNEY.
